DESK SET

Norman C. Gilkison, Elyria, Ohio, assignor to The Gilkison Manufacturing Co., Elyria, Ohio, a corporation of Ohio

Application July 20, 1949, Serial No. 4,031

Term of patent 7 years

(Cl. D33—11)

To all whom it may concern:

Be it known that I, Norman C. Gilkison, a citizen of the United States of America, residing at Elyria, in the county of Lorain, and State of Ohio, have invented a new, original, and ornamental Design for a Desk Set, of which the following is a specification, reference being had to the accompanying drawing, forming a part thereof, wherein

Fig. 1 is a perspective view of a desk set showing my new design; and

Fig. 2, a perspective view of a desk set, similar to Fig. 1, viewed from the opposite direction and illustrating the desk portion in reversed position.

I claim:

The ornamental design for a desk set, as shown.
NORMAN C. GILKISON.
